UNITED STATES PATENT OFFICE.

ALFONS ZYCKI, OF BALTIMORE, MARYLAND.

HALL UTENSIL.

1,348,619.

Specification of Letters Patent.

Patented Aug. 3, 1920.

Application filed June 18, 1919. Serial No. 305,047.

To all whom it may concern:

Be it known that I, ALFONS ZYCKI, a citizen of Poland, residing at 1462 Reynolds St., Baltimore, State of Maryland, have invented 5 certain new and useful Improvements in Hall Utensils, of which the following is a specification.

This invention has as its object the provision of a device for receiving umbrellas, 10 canes and the like so that the same are supported vertically within a space.

A further object is to provide a pan for draining umbrellas, and,

A still further object is to provide means 15 whereby the device may be dismounted, permitting the drainage cup or pan to be removed at any desired time.

These and other like objects are attained by the novel construction and combination 20 of parts hereinafter described and shown in the accompanying drawings, forming a material part of this disclosure, and in which—

Figure 1 is a vertical sectional view taken 25 on line 1—1 of Fig. 3 through the center of a hall utensil made in accordance with the invention.

Fig. 2 is an enlarged fragmentary vertical 30 sectional view of the same, and

Fig. 3 is a top plan view showing the assembled structure.

Referring to the drawings in detail, a cylinder 10 is shown to constitute the base 35 of the apparatus, the same being provided with an imperforate bottom 11, supported upon a plurality of feet 12, the cylinder having at its open top a number of inwardly extending flanged elements 14, while therebelow is an inner band or ring 15, extending 40 interjacent to the walls 10.

Resting upon the ring 15, is the outturned edge 16 of a concave cup 17, notched at the edges so it can be removed or replaced with reference to the inwardly projecting lugs 45 14, and resting upon the edges 16 is a plate 18, having recessed edges adapted to be engaged or disengaged from the flanged edge 14, the plate 18 containing a plurality of openings 19 through which the points of umbrellas or canes may enter, allowing the 50 drippings therefrom to be received in the cup 17.

In the plate 18 is a central circular opening 20, from which extends oppositely disposed side recesses 21. A rod 22 is slidably 55 engaged within the tube 23 adapted to ex-

tend upward from the plate 18 through the tube, the rod 22 having set in its lower end a transverse pin 24, adapted to pass through the lateral recesses 21, while the rod itself 60 is engaged in the central opening 20.

Formed with the rod 22 is a head 25, abutting against which are the coils of a spring 26, its lower end resting in the bottom of a recess 27, formed in the upper end of the 65 tube 23, the effect of the spring being to raise the rod 22 within the tube.

Also extending outward from the central opening 20, are slots 28 which the pin 24 may engage by properly manipulating the 70 handle 25 so that the tube 23 may be rigidly affixed to the upper surface of the plate 18.

Engaged with the exterior of the tube 23 are a plurality of frame elements 29, the same radiating outward and being secured 75 to a circular ring 30, other similar frame elements 31, being formed with inturned terminals 32, adapted to engage with the upper end of the cylinder 10 so as to steady and support the tube and rod inclosed therein. 80 The outer frame elements 29 and 31 are supported in place by a plurality of curved angularly disposed elements 33 and 34 as best shown in Fig. 1.

From the foregoing it will be seen that 85 whenever it may be desired to empty the contents of the cup 17 the same may be removed by properly manipulating the knob 25, releasing the rod 22 from the plate 18 so that the entire superstructure may be removed, whereupon by partially rotating the plate 18 it may be raised and the pan 17 removed in an obvious manner.

Having thus described my invention what 90 I claim as new and desire to secure by Letters Patent, is—

1. In a device of the class described, the combination with a cylindrical base having imperforate walls, and means for supporting said base, of a perforate plate removably 100 engaged in the upper portion of said base, a pan disposed therebelow, means for supporting said pan within said base, a rod removably engageable within said plate, a tube surrounding said rod, spring actuated means 105 for holding said spring rod in a raised position, and a plurality of brace elements engaged with said tube, said brace elements being engageable with the marginal edge of said base.

2. In a device of the class described, the combination with a cylindrical base, an

angular ring set therein, a cup adapted to rest upon said ring, a plate disposable over said cup and means for confining said plate within said base, of a rod having means in its lower end for removably engaging with a central aperture formed in said plate, a tube surrounding said rod, means for normally holding said rod in engagement with

said plate, said means being contained in said tube, means for manipulating said rod, 10 and a plurality of support elements engaging with said tube adapted to be seated upon the marginal edge of said base.

In testimony whereof I have affixed my signature.

ALFONS ZYCKI.
